UNITED STATES PATENT OFFICE.

ALFRED C. GILBERT, OF NORTH HAVEN, CONNECTICUT, ASSIGNOR TO THE A. C. GILBERT COMPANY, OF NEW HAVEN, CONNECTICUT.

CONSTRUCTION TOY.

Application filed March 29, 1923, Serial No. 628,657. Renewed February 13, 1929.

This invention relates to construction toys, and more particularly to toys which may be fabricated or built up from a number of structural units or elements, which are standardized to such an extent that they may be assembled in various ways to build a great variety of different toys. The particular invention described and claimed in this application pertains especially to the means for securing certain of these structural elements together so that they are effectively and securely held in the proper relation to each other, and, at the same time, may be easily taken apart or disassembled so that the elements may be used to construct toys of other forms.

One object of this invention is to provide a simple and effective means for securing together two elements extending at right angles to each other.

Another object of the invention is to provide means for securing together two elements extending at right angles to each other, such that only one bolt or securing member need be used, the members being retained in proper relation to each other by a clamping action of the parts.

A still further object of my invention is to provide a novel form of connector for securing two elements together, which connector is extremely simple in construction and economical to make, and, at the same time, is efficient in operation and may be easily applied and secured in place.

A still further object of the invention is to provide an extremely simple and effective means by which an elongated construction element may be secured in upstanding position upon a flat body member or plate.

To these and other ends, the invention consists in the novel features and combinations of parts to be hereinafter described and claimed.

In the accompanying drawings:

Fig. 1 is a side elevational view of a toy construction embodying my invention; the particular model selected for illustration being a flat car mounted upon a short section of track;

Fig. 2 is a top plan view of the parts shown in Fig. 1;

Fig. 3 is an end elevational view of Fig. 1;

Fig. 4 is a sectional view on line 4-4 of Fig. 2;

Fig. 5 is a top plan view of a section of track of modified construction;

Fig. 6 is an end view of the parts shown in Fig. 5;

Fig. 7 is a view similar to Fig. 5 showing a further modification;

Fig. 8 is an end view of Fig. 7; and

Fig. 9 is a perspective view of one of the connectors or lock members shown.

The particular model which I have selected to illustrate and describe in order to show a preferred embodiment of my invention comprises a flat car 10 mounted upon a section of track 11. The body of the flat car consists of a flat plate member 12 having an integral side flange 13 extending along one side thereof. At the opposite side, a similar flange 14 may be provided by means of an elongated element secured to the body member 12 by angle plates 15. The flat plate or body member 12, as well as the flange 13 and the elongated member 14, is provided with rows of alternately arranged perforations 16 and slots 17; but, while the plate 12 is provided with a number of such rows, I prefer to provide only one row of slots and perforations in the elongated members and in the side flange. Through oppositely disposed perforations 16 in the flange 13 and member 14, a shaft or axle 18 may be passed, and wheels 19 mounted on the projecting ends of these axles. The wheels 19 may be formed with integral hubs 20, through which a set screw 21 may be passed to secure this in place.

It is usual, in assembling sets of construction elements of the kind herein described, to provide a number of units similar to the elongated member 14, which units may be alike in width and cross-section, and also alike in being provided with the alternate perforations 16 and slots 17, but which may vary in length. It is, of course, desirable in the construction of different models to use elements of various lengths, and it has been found quite advantageous to have these elements of the same size as regards width and cross-section, and to have the perforations and slots of the same size and similarly spaced in all. Moreover, it will, of course, be found useful if the slots 17 are of such length that the elongated members may be inserted therein. This is the case in the elements illustrated in this application.

Adjacent each of the four corners of the body plate 12, I mount in an upstanding position a relatively short element 22 by inserting the lower end thereof through one of the slots 17, and securing it in upstanding position by means of an angle clip 23. This angle plate, which may be like the element 15, is L-shaped in section, and may be provided with a perforation 24 in the shorter leg thereof and a slightly elongated slot 25 in its longer leg. Bolts 26 may be passed through this perforation and slot and through aligning perforations in the elongated elements 22 and in the plate 12 to secure the angle plate to the element and to the body member, and, and thus secure the parts rigidly in position.

The upper ends of the upstanding posts or elements 22 may be tied together in pairs by means of passing another elongated element 22 through the slots in the two upright members. To secure this horizontally disposed element in position, I prefer to use a special form of connector or fastening device, shown at 28 in Fig. 9. This connector consists of a flat body portion 29 having a perforation 30 therein, and provided at one end with a U-shaped or clip portion 31 to embrace or fit over the edge of any of the various elements which contain the slots 17. This connector may be applied in various ways, but, in order to secure the horizontal unit 22 to the upstanding posts, I prefer, as shown in Figs. 1 to 3, to slip the U-shaped portion of the connector over the edge of the upstanding post 22, and to secure it by means of a bolt or the like 32, inserted through the perforation 30 and through one of the slots 17 in the horizontal member 22. It will be apparent that after the bolt 32 has been tightened into place, the connector 28 cannot be removed from the upstanding post, but the part of this post between the perforation through which the horizontal unit extends and the edge of the post will be securely clamped between the U-shaped portion of the connector and the horizontal member 22.

In order to build a track from the construction elements which I have described, it is obvious that it is necessary not only to secure the members forming the track rails at right angles to those forming the ties, but it is also necessary to secure the rails so that their edges rest upon the flat sides of the ties. By means of the connectors 28, such an arrangement may be advantageously provided in a number of ways. As shown in Figs. 1 to 4 of the drawings, I may place the elongated elements 33 with their edges disposed upon the upper flat sides of the elongated members 34, which serve as the cross ties. It will, of course, be understood that the members 33 and 34 are of exactly the same construction as the members 14 and 22, except, perhaps, that

they may vary in length when desired. With the members 33 disposed, as described, upon the upper side of the member 34, the connector 29 may be applied with its U-shaped portion placed within one of the slots 17, so that this portion embraces that part of the element 33 between the slot and the lower edge of the element. The flat body portion 29 of the connector 28 may be arranged to project either inwardly or outwardly from the rail members 33, but, as shown in Fig. 4, they project inwardly and bolts 35 are passed through the perforations 30 and through slots 17 in the cross ties 34. It will be apparent that this is an extremely simple and convenient way to connect the rails to the cross ties, and, that by the application of but one bolt 35, the connector members may be secured in place and will clamp the rail members 33 between their U-shaped portions and the cross ties 34.

In Figs. 5 and 6, I have shown a modified form of track construction, wherein the cross ties 34 are passed through the slots 17 in the rails 33 and the connector members 28 are so placed that their U-shaped portions will embrace the lower edges of the rails. This is a reversal of the arrangement shown in Figs. 1 to 4, wherein the connectors are mounted in the slots 17 and the cross ties are placed against the edges of the rails. It will be apparent that in this modified construction, the same clamping action is secured by which portions of the rails are clamped between the cross ties and the connector members, and all of the parts, at any one joint, are held in place by means of a single bolt 35.

In Figs. 7 and 8, I have shown a further modification, which is similar to that shown in Fig. 6, except that the flat body portions 29 of the connectors 28 are arranged to extend outwardly from the rails, the bolts 35, in this instant, being passed through perforations 16 in the cross ties. It will be apparent from an examination of Figs. 6 and 8 of the drawings, that such a construction results in a track of narrower gauge than those previously described.

It will, of course, be understood that my improved connector members 28 may be used in other relations and to connect different units together for various purposes. I have not deemed it necessary nor expedient to illustrate all of the combinations or the relations in which it may be used, but other uses will, of course, suggest themselves to those skilled in the art.

While I have shown and described some preferred embodiments of my invention, it will be understood that the same is not to be limited thereto in all of its details, but is capable of application in other combinations and use in relations other than the particular ones shown herein, without departing from

the spirit of the invention or from the scope of the appended claims.

What I claim is:

1. In combination, two flat elongated elements disposed at right angles to each other, with the end of one element passing through a perforation in the second element, and means to connect said elements together, comprising a connector secured upon the surface of one of said elements and arranged to clamp the other element thereagainst.

2. A toy track structure, comprising a pair of longitudinally extending flat strip members in parallel relation, disposed vertically upon their respective longitudinal edges, each of said strip members having an elongated opening, the openings therein being in opposed relation, a flat tie member extending through the opening in each of said strips, disposed horizontally with respect to said strip members and transversely thereof, and means to secure said tie member to said strip members.

3. In a fabricated toy of the class described, a pair of members of like width and cross section, each of said members having a series of openings therein extending longitudinally thereof, alternate openings in the series being elongated longitudinally and of sufficient elongation to allow the passage of one of the members therethrough, and means securable to one of said members and adapted to embrace a part of the other of said members when one is within

one of the elongated openings in the other 35 whereby said members will be disposed at right angles one to the other with one of said members extending through the other and secured thereto intermediate its ends in any one of a number of positions.

4. In a fabricated toy of the class described, a plate-like member provided with a plurality of parallel series of longitudinally extending openings, alternate openings of each series being longitudinally 40 elongated, a strip member of such width as to be capable of being passed through said elongated openings, said strip member extending through one of said openings in one of the series, said strip member having 45 a series of longitudinally extending openings therein, and means adapted to be engaged with each of said members to retain said strip member vertically disposed to said plate member.

5. In combination, two flat strip-like members, one of said members passing through an elongated opening in the other, and a connector secured upon the surface of the member having the opening and engaging an edge of the other member to clamp the member passing through the opening to the other member against the side edge of the opening.

In witness whereof, I have hereunto set 65 my hand on the 27th day of March, 1923.

ALFRED C. GILBERT.
